UNITED STATES PATENT OFFICE.

NORBERT M. LA PORTE, OF BALTIMORE, MARYLAND.

CONSTANT-LEVEL FUEL-FEED.

1,196,552.

Specification of Letters Patent. Patented Aug. 29, 1916.

Application filed January 5, 1916. Serial No. 70,384.

To all whom it may concern:

Be it known that I, NORBERT M. LA PORTE, a citizen of the United States of America, and resident of the city of Baltimore, State 5 of Maryland, have invented certain new and useful Improvements in Constant-Level Fuel-Feeds, of which the following is a specification.

The applicant has produced a constant 10 head or constant level fuel supply system which is positive in its operation, is not affected by air leaks, clogged with carbon or destroyed by the wide variations of pressure in the combustion chamber. The gaso- 15 lenes is lifted to a supplementary tank by electrical means which may be operated from the ignition system or from some other convenient source of electricity and timed by the engine so that the quantity of fuel 20 lifted bears a direct relation to the engine speed and fuel consumption. The electric means may also include a hand-operated member for controlling the circuit when the engine is idle to generate the necessary head 25 at which fuel is supplied, prior to starting after the engine has been idle for a considerable time.

The lifting means is preferably at the bottom of the entire fuel system so that the 30 last drop of fuel is available and the system may be made insensitive to air leaks as there need be no vacuum. With the device de- 35 scribed for preventing accumulation of fuel above a certain level and means for lifting a quantity of fuel at all times slightly in 40 excess of the consumption and varying with the speed of the engine, a constant head is maintained with the minimum expenditure of energy.

In the accompanying drawings, I have 45 illustrated so much of an internal combustion engine provided with a feeding system embodying the various features of my invention as is necessary to a complete understanding of the inventive idea.

In the drawings, Figure 1 is a side elevation of an automobile engine provided with a constant head fuel feed; Fig. 2 is a central section showing a supplementary or constant head supply tank or chamber; Fig. 3 50 is a similar view of an electrically operated pump with the immediate connections; Fig. 4 is a central section through a carbureter with a constant head tank attached; Fig. 5 55 is a view similar to Fig. 3 showing a dia- phragm pump; and Fig. 6 is a view illus-

trating a modified form of electric means for operating the pump.

Referring to the drawings by numerals, the device comprises an automobile power plant including a gasolene engine 1, a supply tank 2, a supplementary supply tank or constant head chamber 3, carbureter 4 and ignition system 5. The fuel supply tank 2 corresponds to and may be identical 60 in location, capacity, etc., with the supply tanks now used in the simple gravity system. This is connected at or near the bottom by means of a pipe or tube 6 with a pump or equivalent device 7, preferably at 65 or near the lowest point in the system, by means of which the fuel is lifted to the constant head or supplementary tank or chamber 3, the latter being suitably connected to the lift side of the pump by means of a pipe 8 from which constant head tank 3 the gasolene is led to the carbureter by way 70 of the supply pipe 9. As the pump 7 is of a capacity sufficient to more than equal the demands on the engine, the predetermined 75 level in the constant head chamber 3 may be maintained by any suitable means as the well-known float valve or, as illustrated, in the present instance by an overflow pipe 10 having its intake end 11 inside the constant 80 head tank or chamber 3 and at the fuel level intended to be maintained.

The overflow pipe 10, as shown, leads back to the feed pipe 6 at a point between the tank and the pump, preferably near the latter to dispense with friction in handling the overflow and thus reduce the expenditure of energy in operating the pump, which latter, however, is of course very slight.

An important feature of the invention is 95 found in the operating means for the pump. The latter is electrically driven and, as shown in Fig. 3, consists of a cylinder 12 closed at all points except the inlet or suction opening 13 and the outlet or lift opening 14. These are at one end of the cylinder and the pump is single acting containing a piston 15 of magnetic material, as iron or steel, the cylinder being preferably of non-magnetic material, as brass or the like and 100 encircling the cylinder is a solenoid 16 of which the piston 15 is the core. It is evident that but one-half of the stroke can be accomplished by the action of the solenoid and the piston is returned by means of a coil spring 105 113 117 of slight tension. Preferably, there is a cushioning device at the opposite end of the

cylinder which may be in the form of a spring 18 of less tension than the spring 17. While the springs, as shown, are of considerable length, the capacity of the pump, owing 5 to the speed of the motor and small consumption of gasolene per stroke, is necessarily small and for this reason, the stroke of the pump is very short. As illustrated, the working stroke is limited by the shoulder 19 inside the cylinder, the average length of stroke being in the diameter of the piston 10 shown, about $\frac{3}{2}$ of an inch.

In the drawing, Fig. 3, I have shown intake and outlet or suction and lift valves 20 15 and 21 respectively, and suitable connections 6 and 8 with the supply tank and constant head tank 2 and 3.

The operation of the pump shown in Fig. 3 is obvious. Means is provided, as herein 20 after described, for making and breaking the current through the coil 16 of the solenoid. When there is no current, it is obvious that the piston must take a position in which its weight and the tension of the 25 springs are in equilibrium. This position is illustrated in Fig. 3 and when the coil is energized by closing the circuit, the core is drawn downward toward a central position in the coil, the bottom spring being slightly 30 compressed. When the current is again broken, the core moves upward. By continual making and breaking of the circuit, a corresponding continual reciprocation of the piston is maintained. The pumping 35 operation is obvious. On the upward stroke, the gasolene is drawn in or otherwise enters through the inlet pipe 6, unseating the valve 20, and on the downward stroke, the liquid is forced through the pipe 8, the valve 21 being 40 in turn unseated and the valve 20 returned to its seat. In this way, a supply of gasolene proportionate to the frequency of the interruptions of the circuit, is passed upward through the pipe 8 to the supplementary 45 tank or chamber 3.

An alternative form of pump is illustrated in Fig. 5. Instead of a reciprocating piston, I use a diaphragm 25 mounted in a suitable 50 casing 26. The chamber 27 in the casing 26, inclosed on one side by the diaphragm, corresponds in function to the pump cylinder and is provided with an inlet or suction pipe 28 leading to the supply tank 2, and an outlet or delivery pipe 29 leading to the constant head or supplementary tank 3, and in 55 each pipe 28 and 29, there is a suitable non-return valve 30 and 31, respectively. The vibratory motion necessary to expand and contract the volume of the chamber 27 and 60 thus accomplish the pumping action, is communicated to the diaphragm by means of a solenoid 32 with a core 33 engaging the center of the diaphragm in any suitable manner, as by means of a rod 34.

It will be understood that the diaphragm 65

possesses a considerable degree of elasticity so that when flexed, it tends to return to central position as shown. The core 33, on the other hand, is slightly displaced from normal position when the diaphragm takes 70 its central or flat position so that when the circuit is closed and the solenoid, being energized, acts on the core and tends to draw it to central position in the solenoid, a thrust is exerted by way of the rod 34 on the center 75 of the diaphragm and the diaphragm is flexed proportionately to the thrust, contracting the chamber 27. When the circuit is open, the core 33 is released and the thrust being removed from the diaphragm, the latter tends to recover its normal position and, acting through the rod 34, returns the core 33 to the initial position as shown in Fig. 5. In some instances, it has been found desirable to provide a spring 35 of very slight 80 tension, having an action supplementary to the diaphragm, tending to overcome the friction of the parts and return the core to normal position when the circuit is open.

It will be apparent that having the solenoid connected to a source of electricity with suitable means inserted in the circuit for making and breaking the current, a pumping action may be thus set up, the pump chamber 27 being contracted when the current is made and expanded when the current is broken, the valve 30 being unseated, admitting fluid from the tank on the expansion stroke and seated to prevent the return of the liquid to the supply tank on the contraction stroke, and the valve 31 being unseated by the increased pressure, causing the fluid to flow to the supplementary tank 3.

As will be understood from the previous description and preamble, my invention contemplates the use in connection with a supplementary constant head supply tank, of electrical means for maintaining the supply of fuel and therefore the head in the supplementary tank, consisting of an electrically 105 driven pump the operation of which is coincident with and proportionate in speed to the speed of the engine. In what is at present considered the preferred form of the invention, as illustrated herein, the electrical 110 element may be coördinated with the ignition system, the current being made or broken by the ignition timer or distributor, and if the source of current used for the ignition has sufficient capacity, this may be utilized 115 as a means for operating the pump, or the pump may be operated from a separate source of current made and broken by a device independent of the ignition system but operated by the engine, so that the timing is 120 proportionate to the speed of the engine.

Fig. 1 shows my constant head system operated in connection with a low tension ignition of a common and well-known type. This consists of a fly-wheel magneto in- 125 130

- closed in a casing 36 having a terminal at 37 with a lead 38 to the primary coils in the box 42. There is one primary coil to each cylinder and each primary coil is inclosed 5 by a secondary coil connected to a spark plug in the corresponding cylinder. In the operation of the ignition system, the primary coils are grounded in turn by means of the timer 39 to the contacts of which each primary coil is connected by a wire 40 contained 10 in the loom 41 whereby a current is passed through the grounded primary coil and a potential sufficient to give an ignition spark is set up in the corresponding secondary coil.
- 15 In operating the pump from this system, I take into consideration the fact that the capacity of the magneto is large as compared to the demands put upon it by the ignition system. With this fact in view, I find the 20 most efficient operation can be had by connecting the solenoid 16 of the pump to the terminal 37 of the magneto by means of a suitable lead, as the wire 43. Having the plus terminal of the solenoid thus connected 25 to a practically unlimited source of electricity, it is only necessary in order to operate the pump, to ground the other terminal of the solenoid at intervals, the speed of the pump depending upon the intervals of 30 grounding. As the consumption of gasoline is in a way proportionate to the speed of the engine, it is best that the frequency of the grounding should also be proportionate to the speed of the engine and I therefore 35 preferably use a timer which is operated by the engine. In the present instance, as such a timer grounding the engine circuit at intervals, is already provided in the form of the timer 39 in the primary circuit, I find it 40 merely necessary to connect the ground or return wire 44 of the solenoid to one of the ground terminals 45 of the primary coils. In this way, the solenoid is put in parallel or in multiple arc with one of the primary 45 coils and a current is passed through it every time this particular primary coil is grounded, which is once in each cycle or two revolutions of the engine, though the exact frequency of the pump, as compared to the 50 speed of the engine, seems to be immaterial and merely a question of the capacity of the pump and the speed at which it is found desirable to operate it, the fixed requisite being that the pump must be of sufficient capacity 55 to supply a little more gasoline than is necessary to operate the engine at any time and, as this is a function of both the speed and displacement, either can be fixed and the other correspondingly determined.
- 60 In Fig. 6, I have shown in connection with an eight cylinder style of motor having four left-hand cylinders 46 and four right-hand cylinders 47 and an elevated carbureter 48, another embodiment of my invention in 65 which the source of current is a battery or other means independent of the ignition. The current from this source is led through the solenoid as in the forms of the invention already described, and the circuit is made and broken at suitable intervals proportionate to the speed of the engine, by a timing device connected to and operated by the moving parts of the engine.
- Referring to the drawing, I have illustrated in Fig. 6, a battery 50 connected by 75 wires 51 through the solenoid 16 to a terminal 52. The terminal is preferably a spring member and the circuit is made by means of a conducting segment carried by the engine. In the present instance, the 80 segment 55 is attached to one of the timer gears 56 on the cam shaft. As it rotates, it comes in contact with the terminal 52, grounding the battery through the solenoid 85 at intervals and thus energizing the solenoid and operating the pump. It is apparent that by means of suitable gearing or multiplication of the segments, the circuit may be made and broken and the pump may be operated at any desired speed relation with 90 the engine and that this may be accomplished independently of the ignition system, and that the relation is always positive in this as in the other form of the device.
- In order that fuel may be supplied at the 95 necessary head in starting after a long interval of rest or in case of leakage through the carbureter valves, etc., I may provide a hand-operated control for the pump circuit. This is shown in Figs. 1 and 6. In 100 Fig. 1 there is a battery 65 connected to the solenoid 16 of the pump by a wire 66 including a switch 67. On the dash or floor board is a crank 68 carrying a rotary contact 69 with a plurality of contact points 69'. The crank is connected to the engine frame via ground wire 70 and the terminal or brush 71 in the path of the moving contacts 69' is connected to the wire 44 leading 105 from the pump solenoid 16 so that by closing the switch 67 and turning the crank, the battery is grounded at intervals through the pump solenoid 16 and the pump thus 110 manually controlled and operated independently of the engine to give a supply of 115 fuel at normal operating head for starting.
- With the device shown in Fig. 6, it is only necessary to provide means for grounding the circuit beyond the solenoid at intervals. This can be done by a rotary contact 74 120 having numerous contact points 74' actuated by a crank 75, the shaft 72 of the crank being connected to ground and the terminal 73 in the path of the rotary member 74 connected to the terminal of the pump solenoid 16 remote from the battery. By giving the crank a few turns, a charge is lifted when 125 needed to the supplementary tank without operating or turning the engine.

To reduce the number of parts and achieve 130

greater simplicity in the arrangement of the ignition system embodying the constant gravity head principle, I have illustrated in Fig. 4, a carbureter 60 which may be of any preferred type as to the fuel nozzle 61, constant level float chamber 62 and float valve 63, but which is novel in that there is formed integral with or immediately attached to the carbureter body, a constant head or supplementary supply chamber 64. Gasolene is supplied to this chamber by a pipe 8 and the constant level is maintained in any suitable manner as by overflow pipe 10, as in the embodiments already described, but instead of the pipe 9 leading downward to the carbureter, as in the other embodiments of the invention, I have shown an interior passage way 65 controlled by the usual float valve 63, the inlet 11 to the overflow pipe being well above the level maintained by the float 67 so as to give the necessary head and fuel reserve to supply the engine under all conditions.

The functions and relations of the combined parts have been so fully brought out in the preamble and specification that little description of their manner of coöperation is thought to be necessary. The gasolene is led by gravity from the lower portion of the supply tank to the pump which is at a point normally as low as, or lower than, the tank. The pump is electrically operated by a current controlled by a moving part of the engine and the gasolene is lifted positively to the constant head tank in quantities varying with the speed of the engine and more than sufficient to supply the demands of the engine under all conditions, the level being maintained constant in the supply tank by a suitable control as an overflow or the like. From this point, the fuel is led to the carbureter.

While practically all carbureters now offered to the trade have a constant level supply chamber and float valve, the device is so affected by conditions of operation and the requirements to be met are so exacting that the necessity for supplying fuel to the carbureter at a constant head in order to make it possible to maintain a constant level in the supply chamber, is apparent and on this the operation of the fuel nozzle of the carbureter and hence the provision of an efficient mixture, is dependent. The experience of observant operators has both called attention to this necessity and confirmed the correctness of the theory recited.

I have thus described my invention specifically and in detail in order that its nature and operation may be clearly understood; however, the specific terms herein are used descriptively rather than in their limiting sense and the scope of the invention is defined in the claims:

1. In an internal combustion engine, in

combination, a main supply tank for liquid fuel, a carbureter, a supplementary supply tank higher than the carbureter, a pump near the bottom of the fuel supply system, electric means for operating the pump, and means operated by the engine for timing the said electric means for operating the pump. 70

2. In an internal combustion engine, in combination, a carbureter, a main supply tank, a supplementary tank near the transverse vertical plane of the carbureter and higher than the carbureter, a pump for lifting the fuel from the main tank to the supplementary supply tank, and electric means timed by the engine for operating the pump. 75 80

3. In an internal combustion engine, in combination, a main supply tank for liquid fuel, a carbureter, a supplementary fuel supply tank higher than the carbureter and near the transverse plane of the carbureter, 85 a pump near the bottom of the fuel supply system with suitable connections for taking fuel from the main supply tank and lifting it to the supplementary tank, means for maintaining a constant level in the supplementary tank, connections from the supplementary tank to the carbureter, electric means in the form of a solenoid in the core for operating the pump, a source of electricity and means timed by the engine to 90 make and break the circuit and energize the core at intervals determined by the speed of the engine to operate the pump at a speed proportionate to that of the engine. 95

4. In an internal combustion engine, in combination, a main supply tank for liquid fuel, a carbureter, a supplementary supply tank above the normal level of the liquid in the carbureter and near the vertical transverse plane of the carbureter, a pump near 100 the bottom of the fuel supply chamber with connections for taking fuel from the main supply tank and lifting it to the supplementary supply tank, means for checking the accumulation of fuel in the supplementary tank whereby a constant level and a constant gravity head are maintained, connections from the supplementary tank to the carbureter, an ignition system with a source of current and a timing device, and 105 electric means for operating the pump with connections to the source of current and the timer, whereby the operation of the pump is controlled by the timer and hence by the speed of the engine. 110 115 120

5. In an internal combustion engine, in combination, a main supply tank for liquid fuel, a carbureter, a supplementary fuel supply tank extending above the carbureter and near the transverse plane of the carbureter, a pump with suitable connections for taking fuel from the main supply tank and delivering it to the supplementary tank, means for checking the accumulation of fuel in the supplementary tank, whereby a 125 130

- constant fuel level is maintained in that tank, which is above the fuel level in the carbureter, connections from the supplementary tank to the carbureter, an ignition system including a magneto, a primary coil, a timer, a secondary coil, means for operating the pump consisting of a coil and a core with connections to the moving parts of the pump, and means connecting the coil to the magneto and to the timer whereby the coil is energized with a frequency determined by the speed of the engine and the pump is operated at a corresponding speed. 6. In an internal combustion engine, in combination, a main supply tank for liquid fuel, a carbureter, a supplementary fuel supply tank extending above the carbureter and near the transverse plane of the carbureter, a pump near the bottom of the fuel supply system with suitable connections for taking fuel from the main supply tank and delivering it to the supplementary tank, means for checking the accumulation of fuel in the supplementary tank whereby a constant fuel level is maintained in that tank, which is above the fuel level in the carbureter, connections from the supplementary tank to the carbureter, an ignition system consisting of a magneto, a primary coil, a timer, a secondary coil and connections from the secondary coil to the cylinder, means for operating the pump consisting of a coil and a core with connections to the moving parts of the pump, and means connecting the coil to the magneto and to the timer whereby the coil is energized with a frequency determined by the speed of the engine and the pump is operated at a corresponding speed. 7. In an internal combustion engine in combination, a carbureter, a main supply tank, a supplementary supply tank smaller than the main tank, located at a higher level, connected to the carbureter and adapted to feed fuel to the carbureter at a substantially constant head, a pump for lifting the fuel from the main tank to the supplementary supply tank and electric means timed by the engine for operating the pump. 8. In an internal combustion engine, in combination, a main supply tank, a supplementary tank near the transverse vertical plane of the carbureter and higher than the carbureter, a pump for lifting the fuel from the main tank to the supplementary supply tank, electric means timed by the engine for operating the pump, and manually operated means for controlling the electric means to operate the pump independently of the engine in starting. 9. In an internal combustion engine, in combination, a main supply tank for liquid fuel, a carbureter, a supplementary fuel supply tank higher than the carbureter and near the transverse plane of the carbureter, a pump near the bottom of the fuel supply system with suitable connections for taking fuel from the main supply tank and lifting it to the supplementary tank, means for maintaining a constant level in the supplementary tank, connections from the supplementary tank to the carbureter, electric means in the form of a solenoid in the core for operating the pump, a source of electricity, means timed by the engine to make and break the circuit and energize the core at intervals determined by the speed of the engine to operate the pump at a speed proportionate to that of the engine, and manually operated means for controlling the electric means to operate the pump independently of the engine in starting. 10. In an internal combustion engine, in combination, a main supply tank for liquid fuel, a carbureter, a supplementary supply tank above the normal level of the liquid in the carbureter and near the vertical transverse plane of the carbureter, a pump near the bottom of the fuel supply chamber with connections for taking fuel from the main supply tank and lifting it to the supplementary supply tank, means for checking the accumulation of fuel in the supplementary tank whereby a constant level and a constant gravity head are maintained, connections from the supplementary tank to the carbureter, an ignition system with a source of current and a timing device, electric means for operating the pump with connections to the source of current and the timer, whereby the operation of the pump is controlled by the timer and hence by the speed of the engine, and manually operated means for controlling the electric means to operate the pump independently of the engine in starting. 11. In an internal combustion engine, in combination, a main supply tank for liquid fuel, a carbureter, a supplementary fuel supply tank extending above the carbureter and near the transverse plane of the carbureter, a pump with suitable connections for taking fuel from the main supply tank and delivering it to the supplementary tank, means for checking the accumulation of fuel in the supplementary tank whereby a constant fuel level is maintained in that tank, which is above the fuel level in the carbureter, connections from the supplementary tank to the carbureter, an ignition system including a magneto, a primary coil, a timer, a secondary coil, means for operating the pump consisting of a coil and a core with connections to the moving parts of the pump, means connecting the coil to the magneto and to the timer whereby the coil is energized with a frequency determined by the speed of the engine and the pump is operated at a corresponding speed, and manually operated means for controlling the electric means to operate the pump independently of the engine in starting.

electric means to operate the pump independently of the engine in starting.

12. In an internal combustion engine, in combination, a main supply tank for liquid fuel, a carbureter, a supplementary fuel supply tank, extending above the carbureter and near the transverse plane of the carbureter, a pump near the bottom of the fuel supply system with suitable connections for taking fuel from the main supply tank and delivering it to the supplementary tank, means for checking the accumulation of fuel in the supplementary tank whereby a constant fuel level is maintained in that tank, 15 which is above the fuel level in the carbureter, connections from the supplementary tank to the carbureter, an ignition system consisting of a magneto, a primary coil, a timer, a secondary coil, and connections

from the secondary coil to the cylinder, 20 means for operating the pump consisting of a coil and a core with connections to the moving parts of the pump, means connecting the coil to the magneto and to the timer whereby the coil is energized with a frequency determined by the speed of the engine and the pump is operated at a corresponding speed, and manually operated means for controlling the electric means to operate the pump independently of the engine in starting. 25
